UNITED STATES PATENT OFFICE.

DUNCAN L. MELVIN, OF NORTH BROOKFIELD, MASSACHUSETTS.

DESIGN FOR A HAMMER.

SPECIFICATION forming part of Design No. 20,017, dated July 15, 1890.

Application filed June 18, 1890. Serial No. 365,904. Term of patent 14 years.

To all whom it may concern:

Be it known that I, DUNCAN L. MELVIN, a citizen of the United States, residing in North Brookfield, in the county of Worcester and State of Massachusetts, have invented and produced a new and original Design for Bricklayers' Hammers, of which the following is a specification, reference being had to the accompanying drawing, forming a part thereof, which is a perspective view of the hammer-head, showing the side and top.

My design consists in a figure A, in the

form of a parallelopipedon, from one end of which extend the curved figures *a* *b*, of which the figure *b* is the longer, with its base-line *c* 15 formed on a reversed curve.

I claim—

The design for a bricklayer's hammer, herein shown and described.

DUNCAN L. MELVIN.
